UNITED STATES PATENT OFFICE.

SAMUEL E. BAILEY, OF SCRANTON, PENNSYLVANIA.

HYDROPLANE.

1,080,407.

Specification of Letters Patent.

Patented Dec. 2, 1913.

Application filed May 1, 1911. Serial No. 624,339.

To all whom it may concern:

Be it known that I, SAMUEL E. BAILEY, a subject of the King of Great Britain, residing at Scranton, in the county of Lackawanna and State of Pennsylvania, have invented certain new and useful Improvements in Hydroplanes; and I do hereby declare the following to be a full, clear, and exact description of the invention, such as will enable others skilled in the art to which it appertains to make and use the same.

This invention relates to improvements in hydroplanes, and has for an object the arrangement of improved means for controlling the air planes and water planes so that they may interact for assisting each other.

Another object of the invention is the provision of stationary lifting planes, in combination with lifting propellers and movable or adjustable lifting and guiding planes.

A still further object of the invention is the arrangement in a hydroplane, of propelling means and lifting means associated with a prime mover having connected therewith a speed changing device for causing the prime mover to move the propellers at varying speeds as occasion may require, the propellers being associated with lifting and guiding planes whereby the adjustability of the speed of the propellers is utilized.

With these and other objects in view the invention comprises certain novel constructions, combinations, and arrangement of parts as will be hereinafter more fully described and claimed.

In the accompanying drawings: Figure 1 is a side view of an embodiment of the invention. Fig. 2 is a top plan view of the structure shown in Fig. 1. Fig. 3 is a rear view of the structure shown in Fig. 1. Fig. 4 is a front view on an enlarged scale of a steering device. Fig. 5 is a top plan view of the structure shown in Fig. 4. Fig. 6 is a top plan view of the clutch and operating rod, parts being removed to show the operation more clearly. Fig. 7 is an enlarged fragmental detailed view showing means for connecting the water blade cords with the operating shaft.

In constructing a hydroplane embodying the invention it is aimed to secure the highest possible efficiency by causing the various

parts to operate properly and to cause the same to co-act so that one part will assist the other. When the device is being used in the water a number of floats are provided for supporting the structure, but in order to minimize the friction of the floats as the device is propelled along a plurality of blades arranged at the front and rear are provided which action on the water lift or elevate to a certain extent the floats and parts connected therewith for giving a skimming effect. When the machine is being used on land the same is supported by a plurality of traction wheels, but the traction thereof is reduced by the action of the air on all of the air planes as well as on the water planes, so that a minimum amount of power is needed to move the machine. When the machine is used in the air the stationary air planes of course are brought into operation as well as the lifting propellers. These means are sufficient to lift and sustain the machine properly in the air but in order to cause a proper utilization of all possible power the water planes are connected with the adjustable air planes and are caused to act against the air. In this way the various planes always assist each other in any special function which the individual planes are intended to perform. The remaining features of the device are also connected up with the planes and various mechanism so as to coact for securing the best possible results by causing each part to help the other members in the performance of their respective functions.

In order that the invention may be more clearly understood an embodiment of the same is shown in the accompanying drawings, in which 1 indicates a plurality of traction wheels preferably three in number, two being arranged in front and one in the rear. These traction wheels are connected by suitable braces 2 to the frame 3. Connected with the frame 3 by suitable uprights or bracing members 4 are a plurality of floats 5 preferably formed from cork for providing an ample support for the device when floating on the water, but not presenting an unnecessary heavy construction when the device is used as an airship. Mounted on frame 3 is a prime mover 6 of any desired kind which conveys power through a chain 7 to a sprocket wheel 8. Sprocket wheel 8 is

rigidly connected with shaft 9 which shaft is mounted on the floats 5 and which carries at its rear end a propeller 10 adapted to operate in the water for propelling the device along when used in the water. It will be, of course evident that the air propellers 11 and 12 may also be used for propelling the device when in the water if desired. In order to minimize the friction of the floats 10 against the water a plurality of front planes 14 are provided, and also a plurality of rear planes 15. The rear planes are connected to a pivotally mounted arm 16 which has rigidly secured thereto a cross arm 17. Cross arm 17 is connected at its ends with cables 18 and 19 which cables are connected with the opposite ends of arm 20. Arm 20 is rigidly secured to a bell crank lever structure 21 having arms 22 and 23. Arms 22 20 and 23 are connected to the opposite ends of planes 14 by cables 24 and 25. By this construction and arrangement whenever arm 23 is moved both the front and rear planes are moved in the same direction, and for the 25 same distance so that they act in unison for assisting in lifting or guiding the device to the surface of the water. A controlling arm or rod 26 is provided which connects the planes 14 with shaft 27 through a suitable 30 crank connected with the shaft, whereby whenever the shaft 27 is operated the adjustable planes will be moved.

In order to properly guide the device through the water and in the air a rudder 31 35 is provided which extends below floats 5 so as to engage the water when the device is floating thereon. The rudder 31 is pivoted upon an upright 32 in any desired manner, and has secured to the front edge thereof 40 cables 33 and 34, (Fig. 2), which pass over suitable pulleys 35 and 36, and from thence extend to the front and around a pulley structure 37. These pulleys are preferably formed on the order of gear wheels and the 45 cables are also preferably formed as chains so that whenever hand wheel 28 is turned an opposite movement will be given the rudder.

Rigidly connected with the rear part of the frame 3 are planes 39 and 40 which 50 planes are stationary and are held properly in place by suitable braces and connecting bars associated with frame 3. Near the front of the frame 3 is arranged a cross frame 41 which carries upper planes 42, and lower 55 planes 43. Planes 42, 43, 39 and 40 are all held stationary in respect to frame 3, but are set at such an angle to the horizontal as to properly engage the air when the device is properly balanced. Arranged in frame 3 between the sides of planes 42 are a pair of 60 adjustable planes 29 and 30 which may be adjusted simultaneously or independently. The independent adjustment of these planes will cause the device to swerve to one side

and if maintained at different angles will 65 cause the device to circle. The planes 29 and 30 are pivotally mounted upon a shaft 44, and are controlled by rods 45 and 46, which rods extend downward and are connected with shafts 27 and 47 respectively. 70

In order that the shafts 47 and 27 respectively may be rotated in unison or independently of one another I provide a mechanism as shown clearly in Figs. 4 and 5 of the drawing. Upon each of the shafts 27 75 and 47 is a beveled gear 48 which meshes with a companion gear 49 mounted upon a vertical shaft 50 rising from the ends of the shafts 27 and 47 respectively. The upper ends of the shafts 50 are reduced to receive 80 a sliding clutch and gear 51, and the shoulder formed by the reduced portion is notched to receive the clutch of the sliding gear 51. The upper ends of the reduced portions 52 of the shafts 50 carry a hand 85 wheel 53 the function of which is to rotate either of the shafts 50 independently of the other, but as it is necessary to raise the clutch 51 from engagement with the shaft 50 I provide a foot lever 54 pivotally mounted to the frame of the device as at 55 and carrying an arm 56 the upper end of which is forked and engages a grooved collar 57 integral with the clutch 51. The gears on the sliding clutches 51 are adapted to intermesh with an idler 58 which is integral with hand wheel 59 thereon, the purpose of the idler 58 being to cause the shafts 50, 27 and 47 to rotate in unison, and the gear 58 is of greater depth than the gears carried by the 90 sliding clutches 51 so as to permit vertical movement of the gears carried by the clutches 51 and at the same time having the gears intermesh. The construction of the shafts 50, sliding clutches 51, and gears is 95 identical in both cases, and it is seen that by depressing either of the levers 54 the sliding clutch controlled thereby will be raised from engagement with the shaft 50 supporting the same which in turn frees the 100 shaft 50 from the operation of the rest of the gears which in practice permits one of the planes 29 or 30 to be moved in a direction opposite to the other. The hand wheel 28 is secured to a shell having the sprocket 115 wheel 60 adjacent the lower end thereof, and said shell is intended to operate about a shaft or standard 61 secured to the base 62 which in turn is secured to the frame of the machine in any desired manner. The hand 120 wheel 59 and gear 58 are mounted on the upper end of the shaft or standard 61. It is obvious from the construction shown in Figs. 4 and 5 that the rudder may be operated by the hand wheel 28 and gear 60, 125 that several planes may be operated by the shafts 47 and 27 respectively, through the bevelled gears 48 and 49, shafts 50, and sliding

clutches 51, and by the construction of the several parts it is seen that the several parts can move as a unit or independently of one another.

5 Mounted in the frame of the device in the desired location is a motor 63, preferably of the gasolene engine type, the shaft of which is mounted in bearings in the frame, and carries spur gears 64 and 65 which are of uniform size, and secured to the rear end of the shaft are the pulleys 66 which transmit power through the belts 67 to pulleys 68, on one of the shafts 69 or 70 respectively, said shafts being mounted in bearings carried by 10 the frame and supporting the propellers 12 and 13. Arranged to mesh with the spur gears 64 and 65 are the companion gears 71 and 72 which are loosely mounted upon a shaft 73 parallel to the shaft of the driving motor. The gear wheels 71 and 72 are held against longitudinal movement on the shafts by collars, and between said gears is a sliding clutch 74 adapted to engage with one or the other of the gears in the extreme 15 movement of the clutch 74 in either direction. Clutch 74 is splined to the shaft having a longitudinal movement thereon, and is controlled by a longitudinally slidable bar 20 mounted in a bearing 76 carried by the frame, said bar carrying a yoke 77 engaging the annular groove in said clutch. Shaft 73 is mounted in bearings 78 carried by the frame, and secured to the shaft adjacent to each of the bearings is a beveled gear 25 79 meshing with a companion gear 80 which is secured to the vertical shafts 81 and 82 respectively which in turn are mounted in bearings carried by the frame of the machine. Secured to the upper ends of the 30 shafts 81 and 82 are the propellers 83 and 84 respectively which are adapted to be used in assisting the machine to rise from the ground or to maintain its elevation when traveling at a slow speed, and also assisting 35 when alighting.

The forward part of the frame in advance of the operator's seat is provided with a wind shield which is arranged to assist in maintaining the elevation of the machine 40 when in flight, and also to protect the operator from severe cold incident to the higher altitude of the atmosphere.

It is seen from the foregoing that the machine is capable of rolling along the ground, 45 navigating the air, and also floating upon the surface of a body of water, and that the device can be easily launched either from the land or the surface of a body of water. When the device is desired to be raised from 50 the ground it is evident that the same will roll upon the ground until the desired velocity is attained. The resistance on the air of the several planes will cause the device to rise, in the event it is desired to raise

the machine in a limited space the propellers 65 83 and 84 may be rotated at a high speed which in turn acts as a helicopter assisting the planes in raising the device. When it is desired to raise or launch the machine upon the surface of a body of water the propellers 83 and 84 may be rotated the planes 70 14, 15, 29 and 30 being inclined so as to offer a resistance on the water and cause the same to rise therein, and as the machine is advanced and the required velocity is attained 75 the machine will leave the water and soar into the air and by the transmission gears it is seen that the propellers 83 and 84 may be run at any speed desired, as in the case where it is not desired to raise the machine 80 materially but only assist in maintaining the elevation in the event of the machine traveling slower than is necessary to keep the machine in any desired elevation.

What I claim is:

1. In a device of the character described, a frame, a plurality of fixed air engaging planes arranged near the front of said frame, a plurality of fixed air engaging planes arranged near the rear of said frame, 90 a plurality of pivotally mounted water engaging planes arranged near the front of said frame, a plurality of pivotally mounted water engaging planes arranged near the rear of said frame, a pair of pivotally mounted 95 air engaging planes, means for independently shifting the angle of said pivotally mounted air engaging planes, means for connecting said pivotally mounted air engaging planes together for shifting the 100 angle thereof simultaneously, means connecting said water engaging planes with one of said pivotally mounted air engaging planes permitting all of said pivotally mounted planes to be shifted simultaneously, 105 propelling means, and guiding means.

2. An air ship comprising a frame, propelling means mounted on said frame, a fixed lifting plane, a pair of pivotally mounted planes, an adjusting rod connected 110 with each of said planes for adjusting the position thereof, a pair of rotatable shafts, means for connecting the shafts with said adjusting rod for moving the same, a hand operated shaft operatively connected with 115 each of said shafts for rotating the same, a gear wheel rigidly connected with said hand operated shaft, an idler engaging both of said gear wheels, hand operated means for rotating said idler whereby both of said 120 gear wheels are rotated for shifting the position of said planes simultaneously, and means for disconnecting one of said gear wheels from its hand operated shaft for permitting said planes to have the angle thereof shifted independently.

3. In a steering and controlling means for airships, a pair of shafts having crank arms

thereon and connection with movable planes of an airship, of gears thereon, meshing with companion gears on a pair of parallel shafts, clutch members carried by said parallel shafts, gears carried by said clutch members and arranged to mesh with an idler, a hand wheel carried by each of the gears, and means to throw the clutch members out of

register with clutch faces on said parallel shafts.

10

In testimony whereof I affix my signature in presence of two witnesses.

SAMUEL E. BAILEY.
